UNITED STATES PATENT OFFICE

2,541,347

AIR NOZZLE FOR FLUID FUEL BURNERS

Arnold Eckstein, McHenry, and Herman Bogot,
Chicago, Ill., assignors to Ace Engineering Com-
pany, Chicago, Ill., a corporation of Illinois

Application December 23, 1946, Serial No. 718,010

7 Claims. (Cl. 158—1.5)

1

This invention relates to nozzles for fluid fuel burners, and relates particularly to nozzles for controlling the flow of primary air for mixing with the fuel.

The type of nozzle to which the present invention is applied includes a central fuel nozzle, and a surrounding air nozzle having an outlet adjacent the outlet of the fuel nozzle. The fuel emerging from the fuel nozzle diverges, and the air nozzle is designed for directing primary air into the stream of fuel to support combustion.

Such stream of primary air must be accurately controlled to provide efficient combustion. It has been found that a spiralling stream of primary air affords the best mixing of fuel and air.

In all installations it is of course necessary to calculate the amounts of fuel and air required, and it is also necessary to predetermine the required degree of spiralling of the air stream. Whether an efficient flame is produced can be detected instantly by an expert, and when the most efficient flame does not result, it is necessary to change the degree of spiralling of the air after the installation is in. It is almost always necessary to make such changes after the installation is made, in spite of the most thorough and careful calculation made beforehand.

A serious objection to previous devices, and one which the present invention overcomes, is that no means existed for conveniently altering the control of the air. Vanes or baffles were provided in the annular space between the fuel nozzle and air nozzle, and these vanes were angled to produce a circumferential stream of air. In previous devices such vanes were fixed in predetermined position, and when it became necessary to alter the vanes, a major operation resulted.

An important object therefore, of the present invention is the provision of adjustable vanes for controlling the stream of primary air.

Another important object is the provision of means for adjusting such vanes after an installation is made and completed.

A further advantage is that such vanes can be adjusted from outside the outer air nozzle. The vanes are pivoted in the air nozzle and are connected to a ring surrounding the air nozzle, and by rotation of the ring the angle of the vanes can be altered.

A still further advantage is that means is provided for locking the ring and the vanes in position after setting thereof.

With these and other objects in view, our invention consists in the construction, arrangement and combination of the various parts of our device whereby the objects contemplated are attained, as hereinafter more fully set forth, pointed out in the claims and illustrated in the accompanying drawings, in which:

Figure 1 is a longitudinal section through the nozzle of our invention;

Figure 2 is a cross-sectional view taken on line 2—2 of Figure 1;

2

Figure 3 is an elevational view of the nozzle;
Figure 4 is a view taken on line 4—4 of Figure 2;

Figure 5 is a view taken on line 5—5 of Figure 4;

Figure 6 is a view taken on line 6—6 of Figure 1;

Figure 7 is a view similar to Figure 6 showing the vane thereof in a different angular position; and

Figure 8 is an exploded perspective view of one of the vanes and its pivotal supporting means.

Referring now in detail to the drawings, a combination fuel-air nozzle is indicated at 12 shown secured to the outlet element 14 of a burner 15. The fuel-air nozzle 12 includes a central fuel nozzle 16 in the form of a tube diverging toward its outlet, and secured to a fuel line 18 in the burner. The fuel nozzle 16 may be any of a number of conventional nozzles, and does not in itself form a part of the present invention.

Surrounding the fuel nozzle 16 is an air nozzle 20 formed of a tube 22 having exterior threads 25 on its inner end by which it is threaded in a flanged coupling 24 and fixedly secured thereto by means of a set screw 26. The coupling 24 is directly secured to the outlet element of the burner 14 by bolts or screws (not shown).

The inner surface of the outer end of the tube 22 of the air nozzle 20 is curved inwardly, toward the axis, as shown at 28 to form a constricted outlet 30 which closely approaches the fuel nozzle tube 16, at a point slightly inwardly 35 of the outlet thereof. The longitudinal curvature of the portion 28 is approximately the same as the circumferential curvature, the purpose of which will appear later.

Formed on the exterior of the air nozzle tube 40 22, intermediate its ends, is a circumferential bead 32, and spaced forwardly of the bead 32 is a second bead 34, of greater axial extent than the bead 32, and having a rearwardly sloping rear shoulder 36. The bead 34 is provided with a 45 plurality of circular cavities 38 spaced circumferentially therearound, and each opening out of the forward face or shoulder of the bead 34, as indicated at 49 (Figs. 6 and 7).

A plurality of vanes 42 are positioned in the 50 annular space between the fuel nozzle 16 and air nozzle 20. Each vane 42 comprises a body portion 44 having a substantially straight edge disposed toward the fuel nozzle tube 16, and a curved edge opposite thereto, defining a segment of a 55 circle. The curved edge of the vane corresponds to and is necessitated by reason of the circumferential curvature of the inner wall of the tube 22, so that said vanes may be rotated to a position in the tube approaching trans-axial relation. A 60 projection 46 extends from the curved edge of each vane and through a circular opening 48 in the wall of the tube 22. A plurality of openings 48 are provided concentric with the circular cavities 38 respectively.

The mounting means for the vanes 42 consists of a disc 50 having a central axial projection 52. The projections 52 are slotted centrally as indicated at 54, and the slot extends radially through one side of the discs 50. The discs 50 are fitted in the cavities 38 with the projections 52 fitted in the openings 48. The vanes are then inserted into the tube 22, and their projections 46 are then fitted in the slots 54 in the projections 52 of the discs 50, and pins 56 are driven in holes extending diametrically through the discs, and through holes in the projections 46, by access through the openings 48, thereby pivotally securing the vanes in the air nozzle 20. Washers 57 are mounted on the ends of the projections 52, and seat against the inner surface of the tube 22 and against the curved edge of the vanes to insure free pivotal movement of the vanes.

Surrounding the air nozzle tube 22, adjacent its outlet end, is a ring 58 having an inwardly facing interior shoulder 60. When the ring 58 is in position the shoulder 60 bears against the portions of the discs 50 extending out of the openings 48 in the cavities 38. One or more set screws 62 in the inner end of the ring 58 serve to lock the ring 58 in place, relatively to the tube 22, by bearing on the sloping shoulder 36 of the bead 34.

A plurality of pins 64 project inwardly from the ring 58 and extend into the slots 54 in the discs 50, the discs being positioned with the slots 54 registering with the openings 48, and extending toward the outlet end of the nozzle. When the discs 50 are thus positioned, the vanes 42 are positioned longitudinally of the nozzle.

As the fuel emerges from the fuel nozzle 16, it spreads into a cone-shaped stream. Primary air emerges from the outlet element 14 of the burner, and through the annular space between the fuel nozzle 16 and the air nozzle 22. The curved portion 28 and constriction 30 of the air nozzle serve to deflect the air into the stream of fuel and mixes it therewith for supporting combustion.

The next step in the air-fuel mixing operation is the spiralling of the air stream. The vanes 42 are shown in axial alignment in Fig. 1. To position the vanes at an angle, the set screws 62 are loosened, and the ring 58 is rotatably adjusted on the nozzle in one direction or the other to obtain a desired effect in admixing of air and fuel for combustion. As the ring is rotated, the pins 64 operating in the slots 54 of the discs 50 rotate said discs and thereby the vanes 42. The shoulder 60 on the ring bearing on the discs also tends to assist in rotating them. The specific construction of the operating connection between the ring 58 and the discs 50 may be of various forms, e. g., a rack and pinion arrangement might well be employed.

Figure 7 shows one vane 42 in an angled position such as might be employed in an operating installation. With the vanes in such angled positions the stream of air is given a spiralling motion around and into the fuel stream. After the vanes 42 are set in the position desired, the set screws 62 are tightened, locking the ring 58 and the vanes in position. The sloping shoulder 36 of the bead 34 insures that the ring 58 will be wedged into tightly locked position. By such wedging action, the shoulder 60 is brought to bear on the marginal edges of the discs 50, providing a further locking effect on the vanes.

It will be noted that the diametrical extent of the vanes 42 is such as to substantially fill the annular space between the fuel nozzle 16 and the air nozzle 20. Thus, substantially all of the

stream of primary air is effectively baffled in the desired direction. This feature is made possible by the special shapes of the curved portion 28 of the air nozzle and the corresponding curvature of the adjacent edge of the vanes. As the vanes are turned the relative curvature of the vanes and the curved portion 28 remains the same, since the curvature of the portion 28 is the same longitudinally and circumferentially. Such curvature is therefore substantially that of a section of a sphere. As a result, the vanes, in any position, substantially fill the annular space between the fuel nozzle tube and the air nozzle tube, and their foremost tips are disposed adjacent the constriction 30 of the air nozzle tube 22, if not the outlet edge of the fuel tube. The correspondence of the curvature of the vanes and the circumferential curvature of the air nozzle tube 22 is shown in Fig. 2 by the dotted line position of one of the vanes as indicated at 66. In this representation the clearance between the curved edge of the vane and inner wall of the tube 22, is exaggerated for convenience in illustration. Furthermore, the vanes, never, in practical use, are caused to be disposed transaxially of the tube as shown at 68. The position of the vane as indicated at 68 in Figure 2, shows an operative angular position of adjustment of the vane, similar to the position shown in Figure 7.

It will thus be obvious that the positions of the vanes 42 can be quickly and easily varied and the characteristics of the flame varied and controlled, after the complete installation is made, by merely adjusting the ring 58. There is no necessity to dismantle the nozzle, nor replace it with a nozzle having different arrangement and angular disposition of vanes, as has heretofore been the practice. Thus by virtue of the present invention, it is possible to quickly and easily change the size and/or shape or characteristics of the flame to accommodate various sizes and shapes of fire boxes, and to readily compensate for variations in draft conditions encountered in different installations.

While we have shown a particular embodiment of our invention, it will be understood of course that we do not wish to be limited thereto since many modifications may be made, and we therefore contemplate by the claims appended hereto to cover any such modifications or substitutions of equivalents as fall within the true spirit and scope of our invention.

We claim:

1. An air nozzle for a burner nozzle, comprising, in combination, an air outlet tube, a plurality of vanes pivotally mounted in the interior of said tube adjacent its outlet end, said vanes having pivotal portions extending through the wall of said tube, a ring surrounding said tube adjacent the outer end thereof and rotatable thereon, said ring having a shoulder on its inner surface facing inwardly from the outlet end of said tube and having friction engagement with the pivotal portions of said vanes, said tube having a shoulder on its outer surface positioned inwardly of the pivotal portions of said vanes with respect to the outlet end of the tube, and facing inwardly of said outlet end, said ring having projections engaging the pivotal portions of said vanes, and being adapted, upon rotation of said ring, for swinging said vanes about their pivot mountings, and locking means on said ring having friction engagement with the shoulder on said tube for retaining said ring on said tube.

2. An air nozzle for a burner nozzle, comprising, in combination, an air outlet tube, a plurality of vanes pivotally mounted in the interior of said tube adjacent its outlet end, said vanes having pivotal portions extending through the wall of said tube, a ring surrounding said tube adjacent the outer end thereof and rotatable thereon, said ring having a shoulder on its inner surface facing inwardly from the outlet end of said tube and having friction engagement with the pivotal portions of said vanes, said tube having a shoulder on its outer surface positioned inwardly of the pivotal portions of said vanes with respect to the outlet end of the tube, and facing inwardly of said outlet end, said ring being adapted, on rotation of the ring, for swinging said vanes about their pivotal mountings, said shoulder on said tube sloping inwardly from the outlet end of the tube, and locking means on said ring having frictional engagement with said shoulder on said tube.

3. An air nozzle for a burner nozzle, comprising, in combination, an air outlet tube, said tube having an exterior circumferential bead positioned adjacent the outlet end of the tube, said bead having a shoulder facing toward the outlet end of the tube, said bead having circular cavities facing diametrically outwardly of the tube and opening axially through said shoulder toward the outlet end of the tube, a plurality of vanes pivotally mounted in the interior of said tube adjacent its outlet end, said vanes having pivotal portions extending through the wall of the tube and into said cavities, discs fitted in said cavities and rotatable therein, said discs being secured to the pivotal portions of said vanes, said bead having an inner shoulder sloping inwardly of the outlet end of the tube, a ring surrounding said tube and rotatable thereon, said ring having an interior shoulder engaging said discs, said discs having radial slots therethrough, inwardly extending projections on said ring engageable in said slots, said ring, upon rotation thereof, adapted to swing said vanes about their pivotal mountings, and locking means in said ring engageable with said inner sloping shoulder on said tube for locking said ring in a desired position of rotative adjustment.

4. In a burner nozzle construction, a central fuel outlet tube; an outer air nozzle tube surrounding said fuel tube and forming an annular space therewith, a plurality of vanes disposed in said annular space and pivotally mounted in said air nozzle tube, said vanes being pivoted on axes disposed radially of said air nozzle tube and having portions extending through the wall thereof, discs secured to the extending portions of said vanes on the outer surface of said air nozzle tube, said discs being coaxial with said vanes, and a ring mounted on the outer surface of said air nozzle tube and rotatably adjustable thereon, said ring having friction engagement with the peripheries of said discs.

5. In a burner nozzle construction, a central fuel outlet tube; an outer air nozzle tube surrounding said fuel tube and forming an annular space therewith, a plurality of vanes disposed in said annular space and pivotally mounted in said air nozzle tube, said vanes being pivoted on axes disposed radially of said air nozzle tube and having portions extending through the wall thereof, discs secured to the extending portions of said vanes on the outer surface of said air nozzle tube, said discs being coaxial with said vanes, said discs

having slots therein disposed radially with respect to the discs, a ring mounted on the outer surface of said air nozzle tube and rotatably adjustable thereon, said ring having friction engagement with the peripheries of said discs, and pins on said ring extending radially inwardly therefrom and fitted in said slots.

6. In a burner nozzle construction, a central fuel outlet tube; an outer air nozzle tube surrounding said fuel tube and forming an annular space therewith, a plurality of vanes disposed in said annular space, said vanes having flat portions extending through the wall of said air nozzle tube, a disc individual to each vane, said discs being disposed on the outer surface of said air nozzle tube and having slots receiving said flat portions of said vanes, lock pins securing discs to said flat portions of said vanes, said slots extending beyond one edge of said flat portions radially of said discs, a ring mounted on the outer surface of said air nozzle tube and rotatably adjustable thereon, and pins on said ring extending radially inwardly therefrom and fitted in said slots.

7. In a burner nozzle construction, an outwardly flaring central fuel outlet tube, an outer air nozzle tube surrounding said fuel tube, and forming an annular space therewith, said air nozzle tube having a rear substantially cylindrical portion and a forward curved portion forming substantially a section of a sphere, said curved portion forming an annular constriction with said fuel tube adjacent the outlet end of said fuel tube, a plurality of vanes in said annular space, said vanes having pivotal portions extending radially through the wall of said air nozzle tube at substantially the juncture between said cylindrical portion and said curved portion, said vanes having arcuate surfaces conforming to the curved portion of said air nozzle tube, said arcuate surfaces extending beyond both sides of the pivot points of said vanes, said arcuate surfaces forming tapered portions on said vanes, said tapered portions extending into said constriction in one position of said vanes, and a ring mounted on the outer surface of said air nozzle tube and rotatably adjustable thereon, said ring having operating connection with said vanes and being operable on rotation of the ring to swing said vanes about their pivot points.
